FEEDING DEVICE FOR PUMPS

Matthew W. Huber, Chicago, Ill., assignor, by
mesne assignments, to The New York Air Brake
Company, a corporation of New Jersey

Application November 12, 1942, Serial No. 465,362

10 Claims. (Cl. 103—5)

This invention relates to pumps and particularly to means for feeding the intake of a high pressure pump where ordinary suction effects are unreliable or inoperative.

In applicant's prior application, Serial No. 462,563, filed October 19, 1942, there is described and claimed a single-acting multicylinder pump in which the cylinders are parallel and the plungers are actuated by a swash plate. This pump will operate at speeds above 4000 R. P. M. against head pressures of 2000 lbs. per square inch, and was intended for use in the regulating mechanism of a particular variable-pitch propeller for aircraft. In this environment the pump revolves in a circular orbit whose radius is about five inches at a rate of over 1500 R. P. M.

This follows from the fact that the pump is mounted eccentrically in a rotary annular shell which houses the regulator and the pump and serves as a reservoir for the oil which is pumped. Even if this shell, which turns on a normally horizontal axis, be filled to the diameter when the device is at rest, the oil will flow by centrifugal force into a rather shallow annular bath, when the device runs, because of a centrifugal tendency which is many times the force of gravity.

Since the pump cannot be submerged in this annular bath and since the pump inlet is necessarily between the surface of the bath and the center of rotation of the shell, centrifugal forces so resist the entrance of oil into the pump as to preclude the use of an ordinary suction connection.

According to the invention a rather simple pocketed wheel or runner is used to carry oil from the bath to the pump intake. The use of such a runner is facilitated by associating with it a non-rotating concentric shroud so ported that the hydraulic pressure centrifugally developed in the oil bath causes oil to enter the pockets and centrifugal forces also urge the oil to leave the pockets and enter the pump intake. The runner may be incorporated in the gear which drives the pump and this construction saves weight.

This pocketed pump feeder is effective to feed unfailingly from a very shallow bath. This permits reduction of the oil charge to less than half that heretofore necessary, with consequent saving of weight, and substantial elimination of leakage formerly occasioned by submergence of certain packed joints when the device was at rest. These considerations are of obvious practical importance in the aircraft art.

The accompanying drawing illustrates the invention by way of example as incorporated in the particular pitch regulator structure for which it was designed. No details of the pitch regulator are the invention of this applicant, and only such parts thereof as are necessary to description of the construction and utility of the pumping unit, are shown.

Fig. 1 is a fragmentary vertical axial section of the annular rotating housing which encloses the pump (shown part in section, part in elevation), the feeder unit (shown in section) and the regulator (not shown).

Fig. 2 is a fragmentary section on the line 10 2—2 of Fig. 1.

Fig. 3 is an elevation of the pocketed face of the pump driving gear.

Fig. 4 is a fragmentary section on a greatly reduced scale intended to indicate how the pump revolves with the housing and how its gear is driven by the fixed ring gear.

In the drawing the numerals 6 and 7 identify fixed hub parts about which the annular housing comprising two separable main components 8 and 9 rotate. The parts indicated generally at 11 and 12 are seals to resist the loss of oil. A fixed ring gear is formed in the part 6, its teeth being indicated at 13.

The rotating parts 8 and 9 form a hollow annular trough and with the parts 6 and 7 enclose an annular space generally indicated by the numeral 14. This space serves as a reservoir for oil and also houses the pump and some components of the regulator not here material.

35 A pump for a propeller regulator would be of the positive displacement type. The particular pump illustrated has nine single acting cylinders parallel with and arranged in circular series around the drive shaft. The plungers which work in these cylinders are actuated by a swash plate fixed on the shaft.

The pump housing is made in two sections 15 and 16 with mating flanges 17 and 18. The flange 17 engages a mount 19 to which it is bolted. The bolts are not visible in the drawing. When the pump is so mounted, the discharge passage 21 in the portion 15 of the housing communicates with the high pressure passage 22 in a part carried by the annular housing portion 8. A compressed gasket 23 of oil resisting rubber-like material produces the necessary seal.

40 The drive shaft of the pump is indicated at 24 and carries at its outer end a drive disc 25. Fixed to the shaft 24 is a swash plate 26 which turns in a bearing bushing 27 mounted in the portion

16 of the pump housing. A floating plate 28 is interposed between the swash plate and the heads of the plungers, one of which appears at 29. The cylinders are formed in the block 31 which is mounted in the portion 15 of the pump housing. The inlet port to each cylinder leads through its plunger 29 and one such port appears at 32 in Fig. 1. The discharge valves are not visible but they are check valves housed in a discharge chamber connected to the discharge port 21.

The significant thing, so far as the present invention is concerned, is that the liquid to be pumped (in this case, oil) enters the pump housing 16 by way of port 33 (see Fig. 2). Since this port 33 is on the side toward the primary axis of rotation, any oil which enters through the port 33 will be retained within the housing until it is discharged by the pump and will be under a pressure head developed by the centrifugal effect.

The portion 16 of the pump housing has an external configuration intended to facilitate delivery of oil to the port 33. The form of the right hand end of the housing 16 is best shown in Fig. 1. It will be observed that there is an encircling flange 34 which lies in a plane normal to the axis of the shaft 24 and which carries a marginal rim 35 extending outward.

Fixed to the disc 25 and concentric therewith is a combined driving gear and carrier unit, generally indicated by the numeral 36 in Fig. 1, and shown in detail in Fig. 3. The member 36 is concavo-convex, has peripheral gear teeth 37, and on its inner convex side has a series of radial vanes 38, eight being indicated in Fig. 3. The number of vanes is subject to variation. Shrouding the ends of the vanes 38 and dimensioned to make a free running fit within the marginal rim 35 is a rim 39.

Above the pump intake 33 a discharge port 41 (see Fig. 2) is formed in the flange 34. Diametrically opposite this discharge port 41 is an inlet port 42. The oil level in the rotary housing 8, 9 is such that when the housing is rotating at normal speed, the oil is distributed within the housing in an annular bath which will submerge the inlet port 42. The bath can and commonly will be somewhat deeper but all that is strictly necessary is to keep the port 42 submerged, so that only oil will enter the runner 36, filling the buckets or spaces between successive vanes 38.

A deflector 43 is mounted on the portion 16 of the pump housing for the purpose of enclosing a passage from the discharge port 41 to the pump intake 33. The part 43 could be integral with the part 16, but for convenience in manufacture has been constructed as a separate part as indicated in the drawing.

In one respect the runner generally indicated by the numeral 36 is an impeller unit. In another, it is a pocketed carrier. Whichever way it be regarded, the runner 36 is shrouded by the flange 34 with its marginal rim 35 so that oil enters the pockets in the carrier only through the port 42 and is discharged from these pockets through the port 41.

To avoid confusing the drawing, the oil which is a necessary factor in the operation of the propeller control has been omitted from Figs. 1 and 2. Reliance is placed on Fig. 4 to describe the movements of the parts and the level of the oil.

The housing 8, as viewed in Fig. 4, rotates about the axis A which is the primary axis. The runner 36 rotates about a secondary axis B which is parallel with the axis A and which is the axis of rotation of the pump shaft 24. Because the

5 pump is mounted in the rotary housing 8, 9, the pump and consequently the axis B revolve about the axis A. The oil level is designated in Fig. 4 by the broken line C. When the rotary housing 8, 9 is running at a normal rate, say 1500 R. P. M., the oil flows into an annular bath whose level is indicated at C. This bath is under substantial hydrostatic pressure developed centrifugally.

The combined runner and gear 36 rolls around 10 the ring gear 13 and in actual practice has a rotary speed about the secondary axis of the order of 4000 R. P. M. The displacement pump operates against a head pressure which is normally 15 1500 lbs. and may rise to 2000 lbs. per square inch.

The hydrostatic pressure in the oil bath at C (Fig. 4) is effective to develop an active entrance 20 tendency on the oil adjacent the inlet port 42. Consequently the pockets between the vanes 38 fill with oil. This oil is swept around until the 25 pockets open to the discharge port 41. At this time the centrifugal effect incident to rotation about the primary axis A imposes a substantial discharging tendency. This tendency is modified by centrifugal effects developed by the rotation 30 of the runner 36 about the secondary axis. Thus centrifugal effects cause oil to flow through the discharge port 41 and keep the pump intake 33 flooded. The oil delivery capacity of the runner 36 materially exceeds the pumping capacity of the positive displacement pump which in practice 35 is somewhat less than 0.1 cubic inch per revolution, but the runner 36 is impulsive in action and therefore delivers only such oil as the positive displacement pump requires. The charging 40 runner 36 improves the performance of the positive displacement pump, because it delivers to an oil retaining intake chamber which is under a centrifugal hydrostatic pressure, and thus makes it possible to develop a positive pressure on the intake which improves the volumetric efficiency of the displacement pump.

In the regulators as originally designed, the space 14 was filled to the level of the axis A when the device was at rest. This brought the oil 45 above the seals 11 and 12, when the device was not running. The use of the runner to supply the intake to the displacement pump not only ensures proper feeding of this pump even when the oil level is low, but permits the normal oil level in 50 the housing to be lowered to such an extent that it is never above the packed joints 11 or 12.

The incorporation of the runner in the driving 55 gear and the use of portions of the displacement pump housing as a shroud produce a peculiarly compact design which is considered highly advantageous. However, the pump with its charging 60 runner could be used in other environments in which different arrangements of the components would be preferred. In such case, it might not be desirable to combine the runner and the driving gear. The invention may be used to advantage in any relation in which adverse force 65 reactions, such as the centrifugal force discussed above, render the use of a simple suction connection impracticable.

While the invention produces a very compact construction in combination with the particular parallel cylinder pump of my prior application, the runner arrangement could be used to supply 70 pumps of other types. It follows that the embodiment above described in considerable detail is illustrative and not limiting.

I claim:

1. Means for delivering liquid centripetally 75 from a confined annular bath of liquid which re-

tates about a primary axis at sufficient angular velocity to generate substantial centrifugal force, comprising in combination a pocketed carrier revolving about the primary axis and rotating about a secondary axis displaced radially therefrom; and a shroud coaxing with said carrier to close the pockets therein and with respect to which the carrier rotates, said shroud having an inlet port submerged in the bath of liquid and communicating with successive pockets in the carrier and an outlet port nearer the primary axis and also communicating with successive pockets, said ports being so located that the centrifugal force generated by rotation about the primary axis urges liquid into the inlet port and out of the outlet port.

2. Means for delivering liquid centripetally from a confined annular bath of liquid which rotates about a primary axis at sufficient angular velocity to generate substantial centrifugal force, comprising in combination a pocketed carrier revolving about the primary axis and rotating about a secondary axis displaced radially therefrom; a shroud coaxing with said carrier to close the pockets therein and with respect to which the carrier rotates, said shroud having an inlet port submerged in the bath of liquid and communicating with successive pockets in the carrier and an outlet port nearer the primary axis and also communicating with successive pockets, said ports being so located that the centrifugal force generated by rotation about the primary axis urges liquid into the inlet port and out of the outlet port; and a positive displacement pump having an intake fed by said outlet port.

3. The combination of means providing a rotary annular liquid-retaining trough which turns at sufficient speed to distribute the liquid by centrifugal force in an annular bath; a pump rotating with said trough-forming means and having an intake which, at least at times, is radially inward from the surface of the annular liquid bath; shrouding means having an inlet port submerged in said annular bath and an outlet port communicating with the pump intake; a carrier coaxing with and moving relatively to said shrouding means and having at least one pocket which communicates with said ports in alternation; and means for driving said pump and carrier.

4. The combination of means providing a rotary annular liquid-retaining trough which turns at sufficient speed to distribute the liquid by centrifugal force in an annular bath; a pump rotating with said trough-forming means and having an intake which, at least at times, is radially inward from the surface of the annular liquid bath; shrouding means having an inlet port submerged in said annular bath and an outlet port communicating with the pump intake; a carrier coaxing with and moving relatively to said shrouding means and having at least one pocket which communicates with said ports in alternation; and means rendered effective by the rotation of the trough to drive said pump and carrier.

5. The combination of a fixed ring gear; an annular liquid-retaining trough mounted to rotate about the axis of said ring gear at sufficient speed to distribute the liquid by centrifugal force in an annular bath; a positive displacement pump rotating with said trough-forming means and having a driving gear meshing with said ring gear, said pump having an intake which, at least at times, is radially inward from the surface of

the liquid bath; a pocketed carrier turning coaxially with said pump-driving gear; and a shroud coaxing with said carrier and having an inlet port submerged in said annular bath and an outlet port arranged to direct liquid, discharging therethrough by centrifugal force, into said pump intake.

6. The combination defined in claim 5 in which the pocketed carrier comprises a cupped disc with substantially radial vanes and the shroud includes a plate substantially normal to the axis of rotation of the carrier and in which the inlet and outlet ports are formed.

7. The combination of means providing a rotary annular liquid-retaining trough which turns about a primary concentric axis at sufficient angular velocity to distribute the liquid in an annular bath under substantial centrifugally generated hydraulic pressure; a vaned runner revolving about the primary axis and rotating about a secondary axis so located intermediate the primary axis and the annular bath of liquid that the path of the vanes enters the bath; and a liquid confining shroud revolving with the runner, but fixed relatively to the secondary axis and runner, said shroud having an inlet port so located as to permit entrance of liquid from the bath between the vanes of the runner under said hydraulic pressure, and an outlet port so located as to induce discharge of said liquid from between said vanes by forces generated by both rotations.

8. The combination of means providing a rotary annular liquid-retaining trough which turns about a primary concentric axis at sufficient angular velocity to distribute the liquid in an annular bath under substantial centrifugally generated hydraulic pressure; a vaned runner revolving about the primary axis and rotating about a secondary axis so located intermediate the primary axis and the annular bath of liquid that the path of the vanes enters the bath; a liquid confining shroud revolving with the runner, but fixed relatively to the secondary axis and runner, said shroud having an inlet port so located as to permit entrance of liquid from the bath between the vanes of the runner under said hydraulic pressure, and an outlet port so located as to induce discharge of said liquid from between said vanes by forces generated by both rotations; and a positive displacement pump having rotary driving means turning with said runner, and having an intake fed by said outlet port.

9. Means for delivering liquid centripetally from a confined annular bath of liquid which revolves about a primary axis at sufficient angular velocity to generate a substantial hydraulic pressure head in the bath, comprising in combination, a disc which rotates about a secondary axis displaced radially from the primary axis and is formed with pockets in a lateral face; and a plate-like shroud which revolves about the primary axis but is fixed as to the secondary axis and coacts with said disc to close the open side of the pockets, said shroud having approximately diametrically opposed inlet and discharge ports which communicate with the pockets, the inlet port being so located as to be submerged in the bath and the discharge port being at a shorter radial distance from the primary axis than is the surface of the bath.

10. The combination of means providing a rotary annular liquid-retaining trough which turns about a primary concentric axis at suf-

ficient angular velocity to distribute the liquid in an annular bath under substantial centrifugally generated hydraulic pressure; a vaned runner revolving about the primary axis and rotating about a secondary axis so located intermediate the primary axis and the annular bath of liquid that the path of the vanes enters the bath; a liquid confining shroud revolving with the runner, but fixed relatively to the secondary axis and runner, said shroud having an inlet port so located as to permit entrance of liquid from the bath between the vanes of the runner

under said hydraulic pressure, and an outlet port so located as to induce discharge of said liquid from between said vanes by forces generated by both rotations; and a positive displacement pump 5 having rotary driving means turning with said runner, and having an intake chamber fed by said outlet port, and so located relatively to the primary axis that oil is retained in the chamber under a centrifugally developed pressure head 10 and is supplied under said head to the pump.

MATTHEW W. HUBER.
